(57) CLAIM

We claim the ornamental design for a firearm, as shown and described.

DESCRIPTION

FIG. 1 is a perspective view of the firearm showing our ornamental design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof;

FIG. 7 is a bottom view thereof; and,

FIG. 8 is an enlarged view of a portion of the design as seen in FIG. 1.
